UNITED STATES PATENT OFFICE

2,580,225

ROTATING POINTER CHANCE DEVICE

Henry J. Harrison, El Paso, Tex.

Application May 25, 1948, Serial No. 29,130

1 Claim. (Cl. 273—141)

1
This invention relates to advertising novelties and has for its principal object the provision of an intermittently operated clock having a single hand and which will stop on exactly any one of the hour numerals from one to twelve.

A further object of the invention is to provide a novelty which will readily attract attention and which will indicate numbers at random at regular short intervals of time and so designed as to present such numbers in exact conformity with the law of chance, that is, the machine will not favor any one of the chosen numbers and will be brought to a stop exactly on any one number and never between two of the numbers on the clock face.

A further object of the invention is to make an advertising novelty of rugged construction at a minimum of cost and with a maximum of efficiency.

In the drawings:

Figure 1 is a front elevation.

Figure 2 is a similar view but with the front face and supporting disk removed.

Figure 3 is a rear view of the device with the back cover or panel removed.

Figure 4 is a side elevation with the metal strip omitted in part.

Figure 5 is a wiring diagram.

In the drawings which illustrate the commercial form I am now using, the frame consists of two panels 10 and 11 made of laminated wood having between them a platform 12 and having at the top a connecting bracket 14. The front face 15 of the device is a sheet of translucent plastic having engraved on its surface a plurality of clock numerals 16 and an advertising expression as, for example, "Good any hour" indicated by the numeral 17. The plastic clock-face panel 15 is supported from the central frame member 10 by screws passing through spacers 45.

A strip of flexible metal 23, preferably of stainless steel, is secured to the frame member 10 by the relatively small screws 24 so as to give a pleasing effect to the device. I prefer to sever the metal strip 23 as at 25 and 26 and make radial slits 27 in the portion between so that the portions between the slits 27 can be turned down against the panel 10 as best seen in Figure 2, to provide a wide vent 28 in order to carry away the heat produced by the electric lamps as best seen in Figure 4.

A carefully balanced indicator 30 which is substantially an elongated hour hand is mounted on a central shaft 31 which is preferably threaded so that the indicator 30 can be screwed on this

2
shaft and then held in desired position by simple lock nuts.

In order to attract attention to the device I provide a plurality of electric lamps 35 and 36 of alternate color, my preference being red and blue, each of the lamps 35 or 36 being in radial alignment with the numerals 16 to accentuate the latter. At the bottom of the front face of the frame panel 10 I mount a plurality of lamps 38 preferably of a still different color, for example green and these illuminate the legend 17. A very convenient way of mounting these lamps, preferably of small voltage, is to mount them on brackets such as 40 whereby the distance apart 10 or other positioning of the lamps 38 can be adjusted at will and the brackets secured in place as by the screw 41. The lamps 35 and 36 are mounted in a similar manner on a metal disk 44 supported from the panel 10 as by the studs 20 45.

Referring principally to Figure 3 in which the platform 12 is shown but the rear panel 11 is removed for clearness, 50 indicates the motor which drives the shaft 31 on which the hour 25 hand or indicator 30 is mounted. The motor is supported by a relatively heavy bracket 51 secured to the panel 10. On this shaft 31 in addition to the armature of the motor there is mounted a stop wheel 53 of star shape with 30 twelve equally spaced points in exact registry with the numerals 16 of the dial plate 15.

The motor is energized at regular intervals and this spins the shaft 31 with the indicator 30 and the stop wheel 53 for a chosen duration 35 which may be anywhere from a single second to five or more. The purpose of the stop wheel 53 is to insure that the indicator 30 shall point precisely to one of the numerals 16 and never between two of them. To this end I mount a 40 permanent horse-shoe magnet 55 on the central panel 10 by means of a screw 56 and a washer 57 thus enabling me to bring the active end of the horse-shoe magnet to a chosen position with respect to the proximate point of the star stop 45 wheel 53.

The lead-in electric cord 58 is connected as by wire 59 to a manually operated switch 60 which turns the current on and off. The lights, 35, 36, 38, &c., are connected to the secondary 62 of a transformer as by the wires 63 and 67. The primary 61 of this transformer is connected to the manual switch 60 as by the wire 64 on one side and to the lead-in wire 65 of the cord 58 as by 55 the wire 66. Thus whenever the switch is turned

on, the lights are lighted and a synchronous motor 70 is also operated.

The motor 70 drives a small disk 71 carrying one or more pins or cams 72 which engage a flexible spring 73 of switch 74 thus closing the circuit including wires 75 and 76 to the motor 59. Consequently when the manual switch 60 is closed, the various lights immediately light and the synchronous motor 70 starts to revolve making a complete revolution of the driven disk 71 in approximately a minute so that with two pins as shown, at each 30 or 35 seconds one of the pins or cams 72 engages the spring 73 of the switch 74 thus sending current to the main motor 59 which thereupon revolves the shaft 31 and with it the indicator. The time of contact of the cam pins of the synchronous motor with the flexible spring can be varied within considerable limits but I find it sufficient to have the contact about two seconds. The shaft 31 carrying the indicator 30, the star wheel 53 and the armature of the main or shaft motor 59 spins freely after that for a brief period. Then the magnet 55 attracts one of the points, which may or may not be turned in slightly, and holds the shaft 31 so that the indicator points exactly to one of the numerals.

While I have described the best of the commercial models I have built, it is to be understood that the description is for the purpose of illustration and that modifications of the exact structure may be made without departing from the spirit of the invention which is defined in the following claim.

I claim:

A device of the character described comprising a translucent display front face having twelve clock face numerals thereon, a horizontal shaft coaxial with the numerals and projecting thru the front face, an elongated hour-hand indicator balanced on said shaft in front of the face, an armature type shaft motor for driving the shaft by means of its armature on the shaft, a 12-point magnetic star wheel on the shaft between the motor armature and the indicator, a 45 horseshoe type magnet with its gap in approximate alignment with one of the clock face nu-

merals, said magnet being rotatably adjustable about an axis parallel to and spaced from the axis of the shaft so as to bring the indicator into exact registry with one or the other of the two proximate numerals when the shaft is about to stop, a synchronous motor, a slowly rotating cam disk driven thereby, a normally open switch for energizing the shaft motor for intermittent periods of time as the cam disk is revolved by the synchronous motor to close the switch periodically, a transformer having a primary in parallel with the two motors, a series of light bulbs alternately of two contrasting colors radially positioned in rear of the translucent front face, each in registry with one of said numerals, and an additional series of light bulbs of a third color below the clock face numerals, said bulbs all being connected to the secondary of the transformer whereby the lights will continuously be lighted when the device is in operation and the indicator will spin periodically, first under the urge of the shaft motor and then freely with the armature of said motor acting as a fly-wheel and will come to rest at the end of each cycle at random pointing exactly to one of the twelve clock face numerals.

HENRY J. HARRISON.
